(**) Term: **14 Years**

(57) **CLAIM**

The ornamental design for, rear combination lamp for a motorcycle, as shown and described.

DESCRIPTION

(21) Appl. No.: **29/192,279**

(22) Filed: **Oct. 23, 2003**

(30) **Foreign Application Priority Data**

Apr. 24, 2003 (JP) 2003-011669

FIG. 1 is a front elevation view of rear combination lamp for a motorcycle, showing our new design;
FIG. 2 is a rear elevation view thereof;
FIG. 3 is a top plan view thereof;
FIG. 4 is a bottom plan view thereof;
FIG. 5 is a right side elevation view thereof;
FIG. 6 is a left side elevation view thereof;
FIG. 7 is a perspective view thereof; and,
FIG. 8 is another perspective view thereof.
